United States Patent Office.

CHARLES NOBLE, OF PHILADELPHIA, PENNSYLVANIA, ASSIGNOR TO
CHARLES NOBLE & CO., OF SAME PLACE.

Design No. 4,819, dated April 18, 1871.

DESIGN FOR THE PLATES OF A COOKING-STOVE.

The Schedule referred to in these Letters Patent and making part of the same.

I, CHARLES NOBLE, of Philadelphia, county of Philadelphia, State of Pennsylvania, have invented or produced a Design for the Plates of a Cooking-Stove, of which the following is a specification.

In the accompanying drawing which forms a part of this specification—

Figure 1 is a view of one of the side plates of the stove;

Figure 2, a view of the upper front plate; and

Figure 3, a view of one of the legs.

The side plate A of the stove is of the shape shown, is edged with a plain beading, and has three openings or doorways, the large oven-door B only being shown in the drawings. This door is edged with a plain molding, has corner ornaments, and a central ornamental medallion, all being too clearly shown in the drawings to need minute explanation.

The front plate D, fig. 2, has, at the opposite vertical edges, plain moldings, *a a*, two panels, *b b*, with

central oval medallion, and two doors, ornamented, as shown.

The leg, fig. 3, is too clearly illustrated to need description.

Claims.

1. The design for the side plate A and door B, substantially as shown and described.

2. The design for the front plate D with its doors, substantially as shown and described.

3. The design for the foot, fig. 3, substantially as illustrated and described.

In testimony whereof I have signed my name to this specification in the presence of two subscribing witnesses.

CHAS. NOBLE.
